UNITED STATES PATENT OFFICE.

HAROLD LANDON JONES, OF CARTHAGE, NEW YORK.

INTERNAL-COMBUSTION ENGINE.

942,782.

Specification of Letters Patent. Patented Dec. 7, 1909.

Application filed March 22, 1909. Serial No. 485,116.

To all whom it may concern:

Be it known that I, HAROLD LANDON JONES, a citizen of the United States, residing at Carthage, in the county of Jefferson and State of New York, have invented certain new and useful Improvements in Internal-Combustion Engines; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in internal combustion engines, and the object in view is to generally improve upon and render more efficient this type of engines.

More specifically, the present invention comprises an internal combustion engine, without mechanically operated valves, provided with a hollow piston acting as an inlet valve through which the charges of fuel are alternately conducted to opposite ends of the cylinder and exploded, thereby giving an impulse to the piston in opposite directions.

Another and an essential feature of the invention consists in the provision of means whereby the gas mixture under pressure is allowed to expand within the piston, thus serving as a means for cooling the piston and adjacent parts by the expansion of the gas.

The invention comprises various details of construction, combinations and arrangements of parts as will be hereinafter fully described and then specifically defined in the appended claims.

My invention is illustrated in the accompanying drawings, in which I have shown a vertical sectional view through the engine.

Reference now being had to the details of the drawings by letter, A designates the cylinder of the engine which is securely fastened to the upper section B of the compression chamber, and C designates the lower end portion of the crank casing which is securely bolted to the section B as shown. The usual crank shaft D is journaled in suitable bearings in the walls of the crank casing and is connected to the pitman D', which latter is connected to the compressor head E working in a suitable packing ring

about the same within the cylindrical portion of the compression chamber.

A partition, designated by letter F, is interposed between the cylinder A and the section B of the compression chamber, and a hollow piston stem G passes through a suitable packed stuffing box in said partition and has threaded connection with the compressor head E. The lower end of said piston stem is closed and is provided with a lateral opening G' communicating with an opening H in the circumference of the plug I. The plug I is mounted in a threaded aperture H' in the head E and has a double induction valve J mounted therein which controls the openings K and K'. A coil spring J' is mounted upon the valve stem J² and serves to normally seat the valves when the engine is not running. Said plug I has a circumferential opening H which is in registration with the opening E', whereby communication may be had between the hollow piston and the space above or below the head E, accordingly as one end or the other of said valve is opened.

An inlet pipe N communicates with the chamber N' formed in the wall of the section B of the compression chamber and the lower portion of the chamber N' opens through the port N² into the portion of the compression chamber beneath the head E, while the upper portion of the chamber N' communicates with the upper part of the compression chamber above the head E. A double valve, designated by letter L, has a stem L' mounted in a lug L² within the chamber N', and springs L³ bearing between the lug L² and the inner ends of the valves serve to normally hold the valves seated when the engine is not running. An apertured valve carrying plug M is mounted within the chamber N' opposite the opening through which the fuel is introduced and has a circumferential opening in registration with the pipe N and two openings regulated by the double valve L, as shown.

A hollow piston, designated by letter O, is mounted within the cylinder and has an opening in one end in which the hollow piston stem G is fitted, thereby forming a means of communication between the stem and piston head. Said piston head is suitably packed and is provided with two circumferential ports Q and Q' leading through the wall thereof, the former of which is adjacent to one end wall of the pis-

ton head and the other near the opposite end. A duct R is formed in the wall of the cylinder, the ends of said duct leading into the latter and adapted to communicate alternately with one port Q or the other port Q', as the hollow piston head approaches its limit in the opposite ends of the cylinder.

Suitable deflecting plates T project from the opposite ends of the piston head and serve as a means to deflect the fuel as it enters the cylinder at one end or the other of the hollow piston head. An exhaust pipe S leads from an aperture in the wall of the cylinder and affords means whereby the products of combustion may be forced from the cylinder by the inrushing gas as it is admitted alternately to the cylinder above or below the piston head. Sparking plugs, designated by letters P and P', are mounted in the wall of the cylinder, one plug adjacent to each end and affording means whereby the charges may be alternately exploded first at one end of the cylinder and then at the other, thus giving a working impulse to a hollow piston head at each end of its outer throw, thus giving two impulses to each revolution of the crank shaft.

The operation of my engine is as follows. By the reciprocation of the head E in the compression chamber, a charge of fuel is drawn within said chamber by the suction produced within the chamber, and as the head E approaches its limit in either direction, one valve or the other in said head E will unseat and allow the charge to pass through the hollow piston stem G into the hollow piston head O where the gases are allowed to expand and by such expansion produce a cooling effect upon the adjacent parts, both of the stem and piston and which cooling effect, supplemented by the external cooling of the engine, will serve to prevent the engine from overheating. As the piston head O approaches its limit in one direction or the other, communication will be opened between the hollow piston head and one end or the other of the cylinder, thus allowing the fuel to enter the cylinder, and which fuel will be compressed upon the throw of the piston, one charge being compressed by the explosion of the other and not by momentum as is usual with the ordinary engine. In the drawing, the hollow piston is shown as approaching its farthest limit downward with communication between the interior of the piston and the portion of the cylinder above said piston, thus allowing the gasified fuel to enter the cylinder. Upon the downward throw of the piston, the fuel underneath the same will be compressed and fired by the sparking plug P' which will impart a working impulse to the piston and drive the same toward the upper end of the cylinder. When the piston O approaches the position shown in the draw-

ings, the charge below the latter is compressed and fired and the port Q' will be in registration with the port R allowing a charge of fuel to pass into the upper portion of the cylinder after the end of the cylinder has been scavenged and, upon the upper throw of the piston, the charge in advance of the cylinder will be compressed and fired and the lower end of the cylinder will be scavenged. When the port Q comes into registration with the duct R, the gaseous fuel within the hollow piston will force out the products of combustion in the space below the hollow piston through the exhaust port, and the moment the piston closes the exhaust port, the gases underneath said piston will be compressed. It will, therefore, be noted that alternate working impulses will be imparted to the hollow piston as it approaches its limit in opposite directions, affording means for balancing the engine and increasing its power and dispensing with the requirement of a fly wheel.

By the provision of the manner of introducing the fuel through the hollow stem and piston, which serves as an inlet valve, the piston and stem will be cooled by the expansion of gases and two impulses will be imparted to the piston at each revolution of the crank shaft, thus preventing lost motion of the piston. The mixture of air and fuel is taken into the compression chamber below temperature of the atmosphere and compressed and, as it passes through the piston rod or stem into the hollow piston, the compressed mixture expands, and which sudden expansion will produce a low temperature which will have a tendency to effectually cool both the piston stem and adjacent parts and, owing to the gas constantly charging, all whipping of same is prevented.

What I claim to be new is:-

1. An internal combustion engine having a cylinder and a plurality of compression chambers, a hollow piston within said cylinder and adapted to communicate with the latter as the piston approaches its limit in opposite directions, a sparking plug adjacent to each end of the cylinder, a hollow piston stem fastened to and communicating with said piston, a compression head separating said chambers and connected to said stem, and valve regulated means for allowing a gaseous fuel to enter said piston from the compression chambers, as set forth.

2. An internal combustion engine having a cylinder and a plurality of compression chambers, a hollow piston within said cylinder and adapted to communicate with the latter as the piston approaches its limit in opposite directions, a sparking plug adjacent to each end of the cylinder, a hollow stem fastened to and communicating with said piston, a compression head separating said chambers and connected to said stem, a valve

regulated fuel passageway communicating with the compression chambers, and a valve regulated passageway leading through said compression head to said piston stem, as set forth.

3. An internal combustion engine having a cylinder and a plurality of compression chambers, a hollow piston head within said cylinder and adapted to communicate with the latter as the piston approaches its limit in opposite directions, a sparking plug adjacent to each end of the cylinder, a hollow stem fastened to and communicating with said piston head, a compression head separating said chambers and connected to said stem, a valve regulated fuel passageway communicating with the compression chamber said head provided with a port leading into said hollow piston stem, a double valve mounted in an opening in said compression head and adapted to regulate communication between the compression chambers upon opposite sides of the compression head, and the hollow piston, as set forth.

4. An internal combustion engine having a cylinder and a plurality of compression chambers, a hollow piston head within said cylinder and adapted to communicate with the latter as the piston approaches its limit in opposite directions, a sparking plug adjacent to each end of the cylinder, a hollow stem fastened to and communicating with said piston head, a compression head separating said chambers and connected to said stem, said compression head provided with a duct communicating with said hollow stem, a plug seated in an opening in said compression head, a double valve mounted in said plug and regulating ports leading through said plug, the latter being provided with an opening communicating with the duct in said head, and a valve regulated fuel passageway communicating with the compression chambers above and below the compression head, as set forth.

5. An internal combustion engine having a cylinder and a plurality of compression chambers, a hollow piston head within said cylinder and adapted to communicate with the latter as the piston approaches its limit in opposite directions, a sparking plug adjacent to each end of the cylinder, a hollow stem fastened to and communicating with said piston, a compression head separating said chambers and connected to said stem, said compression head provided with a duct communicating with said hollow stem, a hollow threaded plug mounted in an opening leading through the compression head, said plug having a circumferential opening communicating with said duct which communicates with the stem, a double suction and compression valve regulating openings in the ends of said plug, and a valve regulated fuel passageway communicating with

the compression chambers on opposite sides of the compression head, as set forth.

6. An internal combustion engine comprising a cylinder and a plurality of compression chambers, a hollow piston mounted within said cylinder, a compression head separating said compression chambers, a hollow piston stem fastened to and communicating with said hollow piston and connected to said compression head, said cylinder having a port opening in the wall thereof and adapted to form means of communication between a port adjacent to one end or the other of the hollow piston and the cylinder, as said hollow piston approaches its limit in opposite directions, a sparking plug adjacent to each end of the cylinder, and valve regulated mechanism for allowing a gaseous fuel to pass into said hollow stem, as set forth.

7. An internal combustion engine comprising a cylinder and a plurality of compression chambers, a hollow piston mounted within said cylinder, a compression head separating said compression chambers, a hollow piston stem fastened to and communicating with said hollow piston and connected to said compression head, said cylinder having a port opening in the wall thereof and adapted to form means of communication between a port adjacent to one end or the other of the hollow piston and the cylinder, as said hollow piston approaches its limit in opposite directions, a sparking plug adjacent to each end of the cylinder, said compression head having an opening therethrough with a duct leading through the wall of said opening and communicating with a hollow piston stem, a plug seated in said opening and having a circumferential aperture therein, a double valve carried by said plug, a fuel passageway communicating with the compression chambers above and below said compression head, and a double valve regulating said passageway, as set forth.

8. An internal combustion engine comprising a cylinder and a plurality of compression chambers, a hollow piston mounted within said cylinder, a compression head separating said compression chambers, a hollow piston stem fastened to and communicating with said hollow piston and connected to said compression head, said cylinder having a port opening in the wall thereof and adapted to form means of communication between a port adjacent to one end or the other of the hollow piston and the cylinder, as said hollow piston approaches its limit in opposite directions, a sparking plug adjacent to each end of the cylinder, said compression head having an opening therethrough with a duct leading through the wall of said opening and communicating with a hollow piston stem, a

plug seated in said opening and having a circumferential aperture therein, a double valve carried by said plug, a hollow plug mounted in said passageway, and a double valve regulating the openings in the plug within said passageway, as set forth.

9. An internal combustion engine having a cylinder and a plurality of compression chambers, a hollow piston within said cylinder, a hollow stem fixed to and communicating with said piston, a valved piston separating the compression chambers and connected to said stem, valved passageways

leading to the compression chambers and adapted to allow the gaseous fuel to flow therein, and valves in said valved piston through which the fuel is allowed to pass into the hollow piston as it moves in opposite directions, thereby serving to cool the cylinder, as set forth.

In testimony whereof I hereunto affix my signature in the presence of two witnesses.
